U.S. CL. D44—6

FIG. 1

FIG. 2

FIG. 3

FIG. 4

FIG. 5

FIG. 6

FIG. 1 is a perspective view of the combined bread canisters and supporting tray therefor or similar article showing my design;

FIG. 2 is a top plan view;

FIG. 3 is a bottom plan view;

FIG. 4 is a front elevational view;

FIG. 5 is an end elevational view; and

FIG. 6 is a sectional view on line 6-6 of FIG. 1.

In FIG. 1, portions of the canisters are cross-hatched to indicate color contrast therebetween without reference to specific colors. The cross-hatching has been omitted from FIGS. 4 and 5 for convenience of illustration.

I claim:

The ornamental design for combined bread canisters and supporting tray therefor, substantially as shown and described.
